PRINTING MACHINE

Stephen B. Stafford, Oxford, and Herman A. Smith, Holden, Mass., assignors to Rice, Barton & Fales Incorporated, Worcester, Mass., a corporation of Massachusetts

Application June 22, 1939, Serial No. 280,560

9 Claims. (Cl. 101—1)

This invention relates to printing machinery and more particularly to textile printing machines which serve for printing designs in one or more colors on strips of cloth or other suitable material.

Textile printing machinery of the type to which the present invention especially pertains may comprise a large central iron cylinder against which the fabric is supported during the printing operation. This cylinder or roll ordinarily has a lapping made of several layers of cloth wound about it, which provides a resilient or elastic backing for the fabric to be printed. The fabric is led from a supply roll to a position where it passes around this lapping on the cylinder; but a blanket, or endless sheet of rubber or other suitable material, is interposed between the fabric to be printed and the lapping so as to form a more satisfactory backing for the printing operation. A further cloth, known as the back gray, is customarily placed between the fabric to be printed and the blanket so as to absorb any excess ink that may have worked through the fabric. The printing is usually accomplished by means of one or several intaglio rolls mounted on suitable mandrels, which are positively rotated and which serve by frictional contact to drive the backing cylinder.

In a textile printing machine of this type, it is frequently necessary to replace the rubber blanket; but owing to the fact that this blanket is made up as an endless piece, the operation has heretofore required disassembling many parts of the machine and has therefore been laborious, time wasting and costly.

The primary object of this invention is to provide a printing machine of this type which is so constructed and arranged that an endless blanket or other fabric may be readily and easily placed in position around the cylinder and between it and the printing roll. Further objects will be apparent in the following disclosure.

In accordance with this invention, the cylinder is so mounted and arranged that it may be moved readily to a position which permits assembling the endless blanket, and this is preferably accomplished by so arranging the mechanism that the cylinder and one of its bearings may be moved to a position where the endless blanket may be passed around the end of that bearing and into such a position that it may be readily placed around the cylinder.

Referring to the drawings which illustrate a preferred embodiment of this invention as applied to a textile printing machine of standard construction;

Fig. 1 is a fragmentary vertical section of essential portions of the textile printing machine;

Fig. 2 is a fragmentary end elevation of the left hand side frame of the machine;

Fig. 3 is a similar fragmentary vertical elevation of the right hand end of the machine, taken on the line 3—3 of Fig. 1;

Fig. 4 is a fragmentary detail of the hoisting mechanism looking in the direction of the arrow 4 in Fig. 1; and

Fig. 5 is a horizontal section on the line 5—5 of Fig. 3.

The machine illustrated comprises a backing cylinder 10 (Fig. 3) carrying a lapping roll 11 wound thereon. The fabric 12 to be printed is led by suitable rollers to a position where it passes around the cylinder and between the latter and one or more printing rolls 13, two of which are shown, and it is then led to a receiving roll as will be understood. The endless blanket 14 of rubber or other suitable material and the back gray fabric 16 also pass behind the fabric 12 and are suitably carried on rolls supported above the printing members. The printing roll receives its ink from an inking or furnisher roll 18 which in turn receives its printing ink from a trough 20 suitably mounted on the machine. A doctor or scraper blade 22 is so mounted that it will serve to scrape off the excess ink from the printing roll; and these parts may all be constructed and arranged in accordance with standard practice in the industry. For example, the printing rolls may be mounted as shown in the patent to McNicol et al. No. 1,924,614 of August 29, 1933.

As illustrated particularly in Fig. 5, each printing roll 13 is preferably removably mounted on a mandrel 24 which is carried in two bearings 26 suitably mounted in brackets 28 projecting from the side frames 30 and 32 of the machine. The printing rolls have to be held against the cylinder 10 under a high but adjustable pressure, and to that end the bearings of the mandrels are mounted in slide blocks 33 mounted in suitable slide-ways 34 on the brackets, and pressure is applied to these slide blocks 33 by means of manually adjustable screws 36 mounted on the bracket 28 and threaded into an upstanding portion of the bracket as illustrated. Hence, the printing rolls 45 may be moved away from the cylinder or thrust thereagainst under a desired pressure.

Each printing roll is driven by means of a gear 40 on one of its ends which meshes with an intermediate gear 41, which is in turn driven by a suitable source of power. The intermediate gear, in the form illustrated, is mounted on a short shaft 42 which is in turn secured to and projects laterally from a yoke shaped bracket 44 that is bolted to the right hand side frame 30 of the machine.

The shaft carrying the cylinder 10 is mounted in bearings on its opposite ends which are suitably secured in the two side frames, and a problem is presented in the matter of introducing a

new blanket into position for the printing operation, since this blanket is an endless strip of material and must be placed around the main cylinder 10 and between it and the numerous printing rolls. The primary feature of this invention is, therefore, a construction which permits replacement of the blanket readily without removing the cylinder from the machine or disassembling other important parts thereof. To this end, the main cylinder is so mounted that it and its bearings may be moved to a position where the endless blanket may be inserted around the end of one of the bearings, after which the cylinder and bearings may be returned to operative positions. This may be accomplished by so mounting the bearings that one is carried on a short slideway, such as an open ended slot, and may be moved to a position spaced from the frame, while the other bearing may, if desired, remain on its slideway, which thus guides it and keeps the cylinder properly located for return to a printing position. The cylinder is temporarily supported, during the movement, at points which permit a loop of the blanket to be passed over the bearing and so located that it may be subsequently placed around the cylinder 10 and be properly assembled.

As shown in the drawings, the right hand side frame 30 is provided with a long vertical slot 50 (Fig. 3) within which the bearing unit 52 for the right hand end of the cylinder is slidably mounted. The opposed or left hand side frame 32 is provided with an S-shaped bend 54 (Figs. 1 and 2) and a short, open ended, vertical slot 56, and the bearing unit 58 is arranged to be moved up and out of this slot or slideway. This slot 56 is actually entirely enclosed in metal, but owing to its being located in the S-shaped portion of the frame, as shown in Fig. 1, it presents an opening through which the vertically movable bearing may escape. It will, of course, be appreciated that the frame may terminate just above the bearing and thus provide a bearing slot which is fully open at its upper end. Also, many types of slideways or other mounts may be used which permit removal of the bearing; but the illustrated construction has the advantage of not changing materially the mounting of the various mechanisms commonly arranged and supported on the top of the side frame.

The bearings for the cylinder 10 may be suitably constructed, but as shown particularly in Fig. 5, they may comprise two telescoping members 60 and 62 providing outwardly extending flanges 63 and 64 at each side which are adapted to ride in one of the slots 50 or 56 and thus serve as guides which hold the bearings properly located within the slideway. The shaft 66, which carries the cylinder 10, may be suitably mounted in ball bearings 67 located within the members 60 and 62 and other provisions made as required for suitably mounting the shaft of the cylinder 10. It will be noted in Fig. 5 that the shaft 66 is a short shaft extending only into the bearings and does not have any connection with the driving gear 41, since the cylinder 10 is driven only by frictional contact with the printing roll. However, various arrangements may be made for connecting the shaft 68 with other mechanism to be driven in synchronism therewith.

The two bearings of the cylinder 10 are maintained in proper location and alignment against the pressure of the printing roll by two similar adjustable devices, which comprise a screw 70

having a pivot foot 71 bearing against a suitably shaped portion of the outer casing 68 of the bearing. The screw 70 is threaded through a cross bar or thrust member 72 which is of greater length than the width of the slot 50 or 56 in which the bearing is mounted. This bar extends laterally into recesses 74 in the main frame of the machine, which thus form thrust receiving parts that interlock with the bars 72. Another pair of screws 76 is threaded into the frame at the bottom portion of each recess 50, 56, and each has a pivotal engagement with the bottom portion of the bearing block and thus serves as an adjustment limiting the downward movement and position of each of the bearings. The screws 76 are manually adjusted to locate the bottoms of the bearings and the cross bar 72 is thrust upwardly against the top portion of the slot 74 by applying pressure to the screw 70. When it is desired to move the cylinder and the bearings upwardly, then the screw 70 is loosened and the bar 72 swung laterally and removed.

The vertical movement of the cylinder 10 and its associated shaft and bearings may be accomplished by any suitable mechanism, such as that shown in Figs. 1 and 4, which comprises a cross shaft 80 mounted on the two side frames of the machine. This cross shaft has two cylindrical drums 81 secured thereto, as by keys, and a chain 82 is secured to each of these blocks. The lower end of each chain is suitably secured to a yoke 84 made of two parts pivoted together and arranged for surrounding the shaft 86 for ready removal therefrom. The chains may be wound on the drums 81 by rotating the shaft 80 and thus lift the cylinder 10 and its bearings. This rotation of the shaft 80 may be suitably accomplished, such as by means of the hand lever 85 having a yoked end 86 pivotally mounted on one end of the shaft 80. A ratchet wheel 87 located within the yoke 86 is fixed to the shaft and a pawl 88 is pivotally mounted on the lever 85 so as to engage the teeth of the ratchet wheel and turn it in a direction to lift the cylinder 10. A further pawl 89 is pivoted on a short stud 90 to the side frame so as to hold the ratchet wheel 87 in the position to which it is advanced by reciprocation of the hand lever.

The operation of this device will now be apparent in view of the above disclosure. Assuming that the machine parts are in the operative arrangement as shown in the drawings and that it is desired to remove the blanket 14 and replace the same, the bearing screws 36 which hold the print rolls in position are first turned to release the pressure and remove the rolls from contact with the cylinder 10. The cross bars 72 which hold the cylinder bearings in position are released by manipulation of the screw 70 and the thrust bars and screw 70 are then removed from the machine. Then by operation of the hand lever 85, as shown in Fig. 4, the chain hoist is caused to lift the cylinder and its bearings vertically. The right hand bearing of the cylinder remains within its slot 50; while the left hand bearing moves up to the S-shaped portion of the machine and then into the expanded upper portion of the slot 56 as shown particularly in Fig. 2 where it passes freely away from the side frame to the dotted line position of Fig. 1. Then by suitable manipulation of the endless blanket 14, a loop thereof may be passed around the free left hand end bearing and positioned in the space between the chain 82 and the side frame. Thereafter, the cylinder 10 and its bearings may be

lowered into position and the chains and their yokes 84 removed from contact with the shaft 66. Then the blanket may be moved into position around the cylinder 10 and be suitably mounted 5 on the various supporting rolls which carry it in its endless travel.

It will now be appreciated that many modifications may be made and various equivalent constructions employed for the purposes of this invention; hence the above description and the drawings are to be considered as illustrating the principles of the invention and a preferred embodiment thereof and not as limitations on the claims appended hereto.

15 What is claimed as new and protectable by Letters Patent is:

1. A printing machine comprising two opposed side frames, a printing roll and associated driving mechanism mounted on said frames, a cylinder 20 arranged to serve as a backing for the material to be printed by said roll, and bearings for said cylinder which are movably mounted on the side frames, said frame and bearings being so constructed and arranged that the cylinder and its 25 bearings may be moved bodily to a position where one of the bearings is free from its associated side frame so that an endless blanket may be placed around the cylinder.

2. A textile printing machine comprising side 30 frames, a printing roll and associated mechanism mounted on said frame, a cylinder arranged to serve as a backing for the fabric to be printed by said roll, an endless blanket around the cylinder and interposed between it and the printing 35 roll, a bearing for each end of the cylinder mounted in the associated side frame, said side frame having guideways so shaped and arranged that the bearings may be mounted therein and vertically moved to a position where one of the 40 bearings is free from the frame so that the blanket may be passed between the frame and bearing and removed or inserted in position around the cylinder.

3. A textile printing machine comprising two 45 side frames, a printing roll and associated mechanism mounted thereon, a cylinder arranged to serve as a backing for material to be printed by said roll, bearings for each end of the cylinder, means for mounting the bearings on the side 50 frames, said parts being so constructed that the cylinder may be moved to a position where one bearing is free and spaced from its associated side frame for inserting a blanket and wrapping it around the cylinder, and means independent of the bearings whereby the cylinder may be moved to and from said position.

4. A textile printing machine comprising a printing roll, a cylinder arranged to serve as a backing for the material to be printed by said 60 roll, bearings arranged to support each end of the cylinder, two opposed frame members, a slideway on each frame member, guides on the bearings mounted for sliding in said slideways, said parts being so arranged that the bearings 65 may slide to positions where one bearing is free from its slideway and an endless blanket may be passed over the bearing and around the cylinder, and means for lifting the bearings and cylinder for said purpose.

70 5. A textile printing machine comprising a printing roll, a cylinder arranged to serve as a backing for the material to be printed by said roll, bearings arranged to carry the cylinder, two

opposed frame members for supporting the bearings, each frame member having an elongated slideway and the bearings being slidably mounted thereon, one slideway and associated bearing being so constructed that the bearing may be 5 moved off the slideway and be free from its supporting frame for insertion of an endless blanket around the cylinder and means for moving the cylinder and bearings for said purpose.

6. A textile printing machine comprising two 10 opposed machine frames, a positively driven printing roll mounted therein, a cylinder arranged to serve as a backing for the fabric to be printed by said roll, a shaft supporting said cylinder for free rotation so that it may be frictionally driven by the printing roll, bearings for 15 the opposite ends of the cylinder shaft, a vertical elongated slot in each frame forming a slideway, guides associated with the bearings movable in the slideways, one slideway and slot forming an 20 open slot from which the bearing guide may pass to a position where the bearing and cylinder shaft are free from the frame and an endless blanket may be inserted between the machine 25 frame and bearing and positioned around the cylinder, and mechanism whereby the cylinder and its bearings may be moved to permit insertion of said blanket.

7. A textile printing machine comprising two 30 opposed side frames, a printing roll and associated driving mechanism movably mounted on the frame, a cylinder arranged to serve as a backing for the fabric to be printed by said roll, bearings for each end of the cylinder, the side 35 frames having vertical slideways within which said bearings are mounted, one of said slideways being so shaped and arranged that the associated bearing may be removed from contact with the supporting frame for inserting a blanket therebetween, said frame having an opening adjacent 40 to the free bearing arranged for inserting the endless blanket therethrough and around the bearing and cylinder shaft, and means for moving the cylinder and bearings to said positions for said purposes and means for holding the bearings in their operative positions.

8. A textile printing machine according to claim 7 which comprises a removable thrust member and an associated interlocking member on the frame and means for adjusting the position of the bearing which causes the pressure of the printing roll to be absorbed by said thrust member.

9. A textile printing machine comprising a freely rotatable cylinder, a power driven printing 55 roll opposed thereto, two opposed side frames, pressure mechanism for adjustably mounting the roll on the frames and moving it towards the cylinder, two bearings for the cylinder, a slideway on each frame and associated parts on the 60 bearings whereby the bearings and cylinder are movable away from the roll, one slideway being short and the frame so shaped that its associated bearing may be moved to a position where it is free from the frame and an endless blanket 65 may be inserted around the cylinder, means for adjustably positioning the bearings and receiving the thrust of the roll which comprises a thrust member removably interlockable with the frame, and means for lifting the cylinder and its bearings.
